UNITED STATES PATENT OFFICE.

WILLIAM H. MATTHEWS, OF NEWBURGH, NEW YORK.

BEDSPRING FABRIC.

Application filed June 4, 1925. Serial No. 34,937.

- This invention relates to bed spring fabric of metallic construction, and has for its primary object the provision, in a manner as hereinafter set forth, of a fabric of link construction which will stretch and give and be depressed only at that part upon which a body is resting, without disturbing, distorting, or drawing down the fabric remote from the point upon which the body is resting.
- Another object of this invention is the provision, in a manner as hereinafter set forth, of a metallic fabric having a novel sliding or moving coupling link feature which coupling links extend transversely of the fabric between longitudinally extending coupling links and which act by their sliding action to increase the resiliency of the fabric, and further, to allow only that portion of the fabric beneath and immediately adjacent the body of one lying thereon, to be depressed, the other portion of the fabric being horizontal and undisturbed.
- A still further object of the invention is the provision, in a manner as hereinafter set forth, of a bed spring fabric composed of interconnected metallic links, having a novel and improved means for connecting the fabric to resilient spring members positioned between the fabric and the end rails of the spring.
- Another and still further object of the invention is the provision, in a manner as hereinafter set forth, of an improved method of connecting a bed spring fabric to resilient members in turn connected to the end rails of a bed spring, by which means certain alternate resilient members will take up the first of the strain when a body is placed upon the fabric, the other alternate resilient members being reserved to assist the first mentioned alternate members in the event that an unusual weight be placed upon the fabric.
- A final object of this invention is the provision, in a manner as hereinafter set forth, of an improved bed spring fabric structure of interconnected wire link design, which will be light, strong, durable, of wide open mesh and easily kept clean, easily assembled and inexpensive to manufacture.
- The invention will be best understood from a consideration of the following detailed description taken in connection with the accompanying drawings forming part of this specification, with the understanding that the invention is not confined to any strict conformity with the showing of the drawings, but may be changed and modified so long as such changes and modifications mark no material departure from the salient features of the invention as expressed in the appended claims.
- In the drawings:
- Figure 1 is a plan view of the fabric embodying this invention shown as connected to spring members, which in turn are connected to the end rails of a bed spring frame.
- Figure 2 is a perspective view of a portion of the fabric construction and the resilient end connections associated therewith.
- Figure 3 is a plan view of a portion of the fabric showing a slight modification of the link structure.
- Figure 4 is a longitudinal sectional view taken upon the line 4—4 of Figure 3 showing in further detail the method of assembly of the modified structure.
- Figure 5 shows a slight structural change, the transverse links here being offset instead of the longitudinal extending links as in the other views.
- Figure 6 is a further modification of the fabric structure showing a different type of longitudinally extending element and securing means therefor and between the same and the transverse elements.
- Figure 7 is a detailed perspective view of the transverse chain links showing the manner of connecting the same.
- Figure 8 is a detailed perspective view of an end connecting member.
- Figure 9 is a detailed perspective view of certain of the other connecting members.
- Referring now to the drawings in detail, wherein like numerals of reference indicate corresponding parts throughout the several views of the drawings, a pair of bed spring end rails is indicated at 1.
- Arranged along the inner edge of each of the end rails 1, and connected through the apertures 2 therein is a row of alternately long and short expansible springs 3 and 4 respectively. The long springs 3 are all of equal length and the short springs 4 are also of equal length as is clearly shown in Figure 1.
- Connected to the inner hooked end of each long spring and extending inwardly therefrom is a small loop 5 of strong light spring

wire material, and the free ends of each are hooked as indicated at 6, to form a means for connection. It will be noted in the figure that the small wire loops 5 at one end of the fabric have the looped ends connected to the hooks of the springs 3, while at the other end of the fabric the free hooked ends 6 are connected to the hooked ends of the spring 3. It is further to be noted that the hooked ends 6 of the wire links 5 upon one end of the fabric are in vertical position side by side and each is turned downwardly, whereas those loops 5 at the other end of the fabric have their hooked ends 6 in superposed relation one with the other and are horizontally disposed with the ends curved in opposite direction.

Extending from each of the loops 5 at one end of the fabric and connecting with each opposing loop 5, is a link chain, formed of resilient spring wire, each chain in its entirety being indicated by the numeral 7.

Each link of each border chain or outer chain is formed of an elongated substantially U-shaped member 8, the terminal end of each leg of each link 8 being hooked as indicated at 9 to engage the adjoining link 8 or one of the small loops 5 at the end of the fabric. The connected ends and the hooked ends 9 of each of the links 8 are so connected together and to the loops 5 at each end of the chain, that the legs of each link are in the same plane one with the other and with the legs of the loops 5.

The inner leg of each link 8 is looped at its central portion to provide an eye 10, the use of which will be made apparent as the description proceeds.

Each individual link 11 of those chains 7 located between the outer or border chains composed of the links 8, is of elongated U-shaped conformation similar to the links 8, and of the same length, and the free terminal ends of the legs of each of the links 11 are hooked as indicated at 12 to engage in the loop of the adjacent link or in the loop 5 at one end of the fabric as clearly shown in Figure 2 of the drawings.

One leg of each of the links 11, has the central portion thereof offset by bending down as at 13 to form the horizontal lower portion 14 in a lower plane than the rest of the leg and the other leg of the link. This offset portion 14 in one of the legs of each of the links 11 is in direct alinement with the eyes 10 of the links 8 of the border chain.

Extending transversely of the fabric is a series of link chains indicated as a whole by the numeral 15, each link 16 of each chain comprising a substantially elongated U-shaped member of resilient wire, having the terminal end of each leg hooked shaped or formed of an open loop, as indicated at 17 of a size to loosely engage the adjacent link

in the chain or one of the border links 8. That link 16 at the other end of the chain 15 has its head end or looped end connected to one of the eyes 10 of the link 8 of the border chain 7. Each link 16 extends between the legs of a link 11, beneath the straight leg and resting upon the offset portion 14 of the other leg. In this manner it will be seen that the cross chains 15 extend under half of the legs of the links 11 of the longitudinally extending chains 7 and above and rest upon the offset portion formed in each of the other legs and terminate at each end in an eye 10 formed in the inner leg of the link 8 of the border chain 7.

Connected to the inner end of each of the short springs 4 is a substantially V-shaped connecting member 18, the point of joinder 19 between the legs of the member being connected to the end of a spring 4 and the terminal inner end of each leg of each member is hooked as at 20 to engage, at one end of the fabric, with the looped end of one of the terminal links of each of the chains 7 and at the other end with the looped end of a looped member 5.

In Figure 3 there is shown a slight modification of the structure above described, in that the intermediate chains here indicated as a whole by the numeral 7^a are composed of a series of alternate wire links and flat links. In this construction the intermediate chain assembly 7^a comprises terminal link members 21 which are formed of substantially U-shaped resilient wires, similar to the links 11 with the exception that they are much shorter and are without the offset portion in one of the legs. These links 21 have their looped ends in engagement with the ends of the legs of two V-shaped connecting members 18 and with a short link 22 which is in turn connected to one of the springs 3. The free end of each leg of each link member 21 is hooked as at 22 and engaged through apertures 23 in one end of a pair of superposed plate members 24 and 25 respectively, the plate 24 being the upper plate and 25 indicating the lower plate. The other end of each of these plates has a similar aperture 23 therethrough in which is connected one looped end 26 of a straight single link 27. These intermediate chains are made up of alternate straight links 27 and superposed connecting links 28 or plates 24 and 25 as shown in Figures 3 and 4 of the drawings.

The cross chains 15 are the same as those set forth above and as shown in connection with Figures 1 and 2, the legs of each link 15 of these cross chains 15 pass between the plates 24 and 25.

The outer or border chain structure 7 is the same as those shown and described in connection with Figures 1 and 2 and the

cross chains connect in similar eyes 10 formed in the inner leg of each of the links 8 of this chain.

In Figure 5 there is shown a slight modification of the structure disclosed in the other figures. In this form the arrangement of the links is reversed, for here the links of the transverse chains, one of which chains is indicated at 15', are formed in a manner similar to the links 11, and the links in the longitudinal chains 7' are like those in the chains 7. Each link 16' comprises a wire body bent upon itself to set up the substantially parallel legs shown.

One leg of each of these links is bent downwardly adjacent each end as at 13' to provide the offset straight portion 14'.

Each of the links 11' comprises a wire body bent upon itself as shown to provide both of which legs pass between the leg of a link 16', resting upon the offset portion 14' as shown in Figure 5.

The means for interconnecting the links in this form are, as shown, the same as in the first mentioned form.

A still further modification is shown in Figure 6 of the drawings, as the longitudinally extending elements here are formed of relatively small steel cables 30 which are formed of a series of twisted together strands much in the same manner as heavy steel cables are formed.

Each end of each of these longitudinally extending elements 30 is passed up through an aperture 31 in an elongated steel plate 32, across the top and longitudinally of the plate and down through a second aperture 33 at the other end thereof, and there is also passed through these apertures 33 the inner hooked end of a long spring 3 the other end of each of these springs being secured to the end cross bar 1 of the bed frame as in the other cases. The threading of the ends of the elements 30 through the apertures 31 and 33 of the link plate 32 is such that when the element 30 is drawn taut it binds itself securely in the apertures of the plate and is therefore prevented from becoming disconnected therefrom.

Each of the longitudinally extending elements 30 carries thereon a series of spaced triangular plates 34 and each of these plates is provided with three apertures, 35, 36, and 37 respectively as shown. The plates are mounted upon the longitudinally extending elements 30 by having the elements threaded up through one of the apertures, aperture 35, across the face of the plate and down through the opposite aperture, 36, as shown. The plates therefore have one side parallel with the element upon which is mounted one angled portion of each thereof extending inwardly from the elements 30 carrying the plate.

Those elements 30 which are located within or between the border elements, each have thereon a pair of square plate members 38, each being located adjacent one end of its supporting element. Each of these plates as shown has four apertures formed therethrough one adjacent each corner of the plate, as indicated by the numerals 39, 40 and 41. As is shown the supporting element 30 of each plate is passed up through one aperture, aperture 39, across the top of the plate and down through aperture 40 which is located in the opposite corner of the plate. The drawing tight of the supporting element 30 securely binds the plate in any desired position thereon. These plates 38 are in alignment transversely of the bed fabric and an end 1 of the triangular plates 34 upon the border element 30 is also positioned in alignment with the plates 38 as is shown in Figure 6.

Connecting the transversely extending row of plates 34 and 38 with the short spring elements 4 which are connected to the end cross member of the frame 1, are substantially V-shaped link members 18 similar to those shown in the other figures. The apex of each of these V-shaped link members is engaged by the springs 4 and the terminal ends of the legs thereof are secured to certain of the plates 34 or 38, as is shown, in the apertures in the adjacent sides of the plate.

Connecting those triangular plates which are carried upon the border elements 30 and which are located between the end triangular plate 34, are transversely extending link chains indicated generally by the numeral 42 and formed of links 43 and 44 respectively. The links 43 constitute the end links of the chain 42 and the links 44 the intermediate links of the chain. The end links are connected in the innermost aperture 37 of the triangular plates 34 as shown, and the legs of these terminal links are superposed except that the inner ends where the under leg is bent upwardly to bring the inner end in parallel relation in the same plane with the upper leg as clearly shown in Figure 7, and these terminal ends of the legs are hooked as at 45. These hooks engage over the looped ends of the inner links 44, the legs of which inner links are, as shown, in the same plane with the exception of the central portion of one leg which is bent downwardly as indicated at 46. As shown in Figure 6 the longitudinally extending elements 30 extend between the legs of the link members 43 and 44 and thus there is set up a looped connection between the transverse chains and the longitudinally extending elements.

When the fabric herein described is put into use, the action of the parts is, when a weight is placed thereon, as follows:

Assuming that the weight is evenly distributed over the first three of the interme-

diate chains 7 adjacent the border chain, the first action, is of course, the depression of the links 11. This depression of the links 11 draws upon the loops 5 stretching first the large springs 3. The cross chains 15 will be carried down with the links 11, and the links 16 of the cross chains, which connect those links directly beneath the weight upon the fabric with those at the side where there is no weight, will assume an inclined position swinging upon the portion 14 of the depression in the leg of the link 11 through which it extends. This instead of drawing down on the chains 7, which carry no weight, leaves them perfectly horizontal and tight, the inner leg of each link of the border chain being the only portion of the fabric not actually in contact with the weight, which is deformed.

If the weight is not unusual upon the fabric, the large springs 3 will support most of it as the V-shaped connecting members 18 will first have the terminal ends of their legs drawn together before any direct pull is had upon the short springs 4 but, when additional weight is put upon the fabric the short springs 4 are brought into play and assist in supporting the load.

It will be thus seen that there is here provided a fabric structure of improved design which, when the body is placed thereon, will not be inclined from each outer edge to the point where the body is laying, but will only be depressed at that point which supports the body and the remainder of the fabric will be perfectly horizontal and unchanged.

Having thus described my invention what I claim is:—

1. A bed spring fabric, comprising a longitudinally extending parallel series of link chains, each link being of elongated substantially U-shaped contour, means for setting up a resilient connection between the end of each chain and an adjacent spring frame end bar, and a transversely extending parallel series of link chains, each of elongated substantially U-shaped contour and having the end link of each chain fixed to a link of an outer longitudinally extending chain and the other links of the body of the

chain slidably extended between the legs of the links of the longitudinal elements substantially midway their length.

2. A bed spring fabric, comprising a longitudinally extending parallel series of link chains, each link being of elongated substantially U-shaped contour, the inner leg of each link of each border chain being formed to provide an eye and one leg of each link of each of the other chains having a depressed offset portion therein, said eyes and offset portions being in alignment transversely of the fabric, means for setting up a resilient connection between each end of each chain and a spring frame end bar, and a transversely extending parallel series of link chains, the end link of each being fixed in one of said eyes and the intermediate links being loosely extended between the legs of the links in the longitudinally extending chains and seating in said depressed portions.

3. A bed spring structure comprising, in combination, a pair of end rails each having along the inner edge thereof a longitudinally extending row of apertures, alternate long and short spiral springs each having one end engaged in one of said apertures of each rail, a short link member extending inwardly from the inner end of each of said long springs, a chain structure having the links thereof of elongated substantially U-shaped formation connecting those short links at one end of the structure with those in opposed position at the other end of the structure, transverse chains composed of elongated substantially U-shaped links, having each end link connected to a link of an outer one of said first mentioned chains and having the other links extended through the links of the other of said first mentioned chains, and V-shaped connecting members each connected at its apex to one of said short springs, and having the terminal portion of each leg in connection with one end link of one of said first mentioned chains.

In testimony whereof, I affix my signature hereto.

WILLIAM H. MATTHEWS.
